Primary Examiner — David Muller*Assistant Examiner* — Abraham Bahta(74) *Attorney, Agent, or Firm* — Winthrop & Weinstine, P.A.(57) **CLAIM**

The ornamental design for a peanut pouch, as shown and described.

DESCRIPTION

FIG. 1 is a perspective view of the peanut pouch showing the design.

FIG. 2 is a right side view thereof.

FIG. 3 is a left side view thereof.

FIG. 4 is a top view thereof.

FIG. 5 is a bottom view thereof.

FIG. 6 is a front view thereof; and,

FIG. 7 is a rear view thereof.

The portions of the disclosure shown in broken lines form no part of the claimed design.
